UNITED STATES PATENT OFFICE

159,766

FROZEN FOOD BOX

Lovic Cyril Warren, Jr., Atlanta, Ga.

Application July 12, 1949, Serial No. 3,854

Term of patent 14 years

(Cl. D67—3)

To all whom it may concern:

Be it known that I, Lovic Cyril Warren, Jr., a citizen of the United States of America, residing at Atlanta, in the county of Fulton and State of Georgia, have invented a new, original, and ornamental Design for a Frozen Food Box, of which the following is a specification, reference being had to the accompanying drawing, forming a part thereof.

In the drawing:

Figure 3 is a rear elevational view of the same with the top in closed position and with the transparent top supporting wings in stored position in the rack at the rear of the box.

The external areas of the top and side of the food box not shown in the drawings are substantially plain.

I claim:

The ornamental design for a frozen food box, as shown and described.

LOVIC CYRIL WARREN, JR.
